BYERS W. KADEL, OF BALTIMORE, MARYLAND.

CAR TRUCK.

Application filed August 16, 1927. Serial No. 213,340.

This invention relates to railway trucks and more particularly to the construction of the side frames thereof whereby increased strength is secured as well as increased 5 spring capacity provided.

The principal object of my invention, generally considered, is the improvement in car trucks, particularly the construction of the side frames thereof, whereby provision is 10 made for supporting an increased number of bolster springs, the outer of which are positioned at a higher level than the inner or main group thereof, said outer springs being supported on embossments providing 15 at the same time for increasing the strength of the tension member.

An important object of my invention is the provision of car trucks formed with side frames in which the tension member between 20 the bolster guide columns is formed with a central horizontal portion and inclined end portions, the junctions between said central and end portions being reinforced by upward embossments, the upper 25 surfaces of which serve as auxiliary spring supports and the inner sides of which preferably slope downwardly and inwardly in approximately the same direction as the inclined end portions of said tension member, 30 thereby providing supplemental truss portions for said tension member, said supplemental truss portions at the same time providing means for interlocking the associated spring plank with the frame.

Another object of my invention is to provide 35 an integral side frame with a tension member serving to support the bolster springs at a plurality of elevations and for that purpose being provided with upwardly embossed end portions adjacent the bolster guide columns, said upwardly embossed portions being formed with an upper horizontal web and inclined inner sides providing a reinforcement adjacent the junction 40 between the horizontal and inclined portions of the tension member, the ends of said reinforcement tapering with respect to said tension member and merging therewith.

Other objects and advantages of the invention 50 relating to the particular arrangement and construction of the various parts will become apparent as the description proceeds.

Referring to the drawings illustrating my

invention, the scope whereof is defined by 55 the appended claims:

Figure 1 is a side elevation of a truck particularly showing a portion of a side frame thereof partly in longitudinal section, with the associated spring plank, bolster and 60 nest of bolster springs.

Figure 2 is a horizontal sectional view on the line 2—2 of Figure 1, looking in the direction of the arrows.

Figure 3 is a transverse sectional view on the line 3—3 of Figure 2, looking in the direction of the arrows.

Figure 4 is a plan of the associated spring plank.

Referring to the drawings in detail, like 70 parts being designated by like reference characters, there is shown a portion of a truck comprising side frames 1 preferably formed of cast steel, although it will be obvious that I do not wish to be limited to 75 such construction. Each frame 1 comprises a compression member 2, a tension member 3, and bolster guide columns or strut portions 4 spacing intermediate portions of said compression and tension members and leaving a window opening 5 therebetween. The compression and tension members at the ends thereof join with one another and may be either formed with integral journal boxes or be adapted for connection with 80 journal boxes in any desired manner as will be understood by those skilled in the art.

The tension member 3 between the bolster columns 4 is in the present embodiment generally box-shape in cross-section and comprises an upper web 6 forming a spring plank seat portion, a lower web 7 and side webs 8. In order to provide the necessary area for supporting the nest of springs 9, illustrated diagrammatically in dot and dash lines, the web 6 is preferably extended beyond the side webs 8 and reinforced with respect thereto by triangular gussets 10. The tension member in the present embodiment involves a relatively short central horizontal portion 11 joining with inclined end portions 12 substantial distances inwardly of the bolster guide columns 4 whereby the junctions with said bolster guide columns are elevated a substantial distance above the main spring supporting web 6 of the tension member.

The nest of bolster springs in the present

embodiment involves a main five-unit nest supported on the spring plank 13 which extends between the frames of the truck and in turn rests on the upper web 6 of the tension member which provides a spring plank seat portion, the upper surface of which may be provided with the usual squaring lugs 14, and auxiliary springs 15 disposed longitudinally on either side of the main nest of springs. For supporting said auxiliary springs the upper web 6 of the tension member is upwardly convoluted or provided with bosses 16, the outer ends of which extend from approximately the junctions of the inner webs of the bolster guide columns and the inclined upper webs 6 of the tension member 3, said bosses 16 comprising horizontal web portions extending inwardly and each of sufficient area for properly supporting a spring unit 15. The upper surface of each boss may desirably be provided with a spring centering lug 17. The inner sides of said auxiliary spring supporting portions 16 are preferably curved to correspond with the outline of the associated springs and joined to the main horizontal portions of the web 6 by downwardly and inwardly inclined webs 18, said webs preferably extending approximately parallel to the inclined end portions 12 of the tension member and also preferably decreasing or tapering in width in order to pass between the adjacent transversely spaced spring units of the main nest of springs 9, preferably intersecting the transverse axial planes of said spaced units and finally merging with the web 6 of the tension member. The associated spring plank 13 is formed to cooperate and interlock with the bosses 16 and particularly the sloping inner sides 18 thereof and for that purpose is provided with upwardly and outwardly tapering corrugations which adapt said plank for snugly fitting over the sloping sides 18 of the bosses 16.

45 The associated bolster 19 is formed with a main portion 20, the lower surface of which rests upon and is supported by the main nest of springs 9 and side portions 21, the lower surfaces of which are elevated with respect to the lower surfaces of the main portion 20 an amount corresponding to the difference in elevation between the auxiliary spring supporting bosses 16, and the main spring supporting portions on the spring plank 13, whereby the auxiliary springs 15 may be of a height corresponding with the height of the main springs 9.

From the foregoing disclosure it will be apparent that I have devised a side frame in which the tension member between the bolster guide columns is reinforced adjacent the junctions between the horizontal central portion and the inclined end portions thereof by upward embossments which not only serve for supporting auxiliary springs, but

efficiently reinforce said tension member at critical sections thereof and provide for interlocking the associated spring plank with respect to said frame.

Having now described my invention, I claim:

1. A side frame comprising a compression member, a tension member, struts spacing intermediate portions of said members and leaving a window opening therebetween, a web of the tension member beneath the window opening forming spring supporting portions on a plurality of levels, and a sloping web joining said spring supporting portions. 80

2. A side frame comprising a compression member, a tension member, struts spacing intermediate portions of said members and leaving a window opening therebetween, the upper web of the tension member beneath the window opening forming spring supporting portions arranged at different levels, and sloping webs joining said spring supporting portions at different levels. 85

3. A side frame comprising a compression member, a tension member, struts spacing intermediate portions of said members and spaced to leave a window opening therebetween, the upper web of said tension member beneath the window opening providing a main spring seating portion, portions of said web adjacent the bolster guide columns being offset upwardly to provide auxiliary spring seating portions, said auxiliary spring seating portions being joined to the main spring seating portions by webs sloping downwardly and inwardly toward each other. 90

4. A side frame comprising a compression member, a tension member, struts spacing intermediate portions of said members and leaving a window opening therebetween, said tension member beneath the window opening having a substantially horizontal central portion and upwardly and outwardly inclined end portions, said central portion being formed with an upper web serving for the support of a main group of bolster springs, and the inclined portions of said web adjacent the junctions with the bolster guide columns being extended in a substantially horizontal direction toward the center of the frame above the main spring supporting portion to provide auxiliary spring supporting portions, the inner ends of said auxiliary spring supporting portions being connected to the main spring supporting portions by inclined webs extending substantially parallel with the inclined end portions of the tension member. 110

5. A side frame comprising a compression member, a tension member, struts spacing intermediate portions of said members and leaving a window opening therebetween, 120

said tension member comprising inclined end portions extending inwardly beyond said struts and connected by a substantially horizontal central portion, the upper web of 5 said central portion being widened for the support of bolster springs and provided with portions upwardly offset to approximately the intersection of the inclined end portions with the struts, said upwardly offset 10 portions serving for the support of auxiliary springs and the inner edges thereof being joined to the main supporting portion by webs extending approximately parallel with the inclined end portions of the 15 tension member.

6. A side frame comprising a compression member, a tension member, bolster guide columns spacing intermediate portions thereof and leaving a window opening therebetween, 20 that portion of the tension member beneath the window opening comprising a horizontal central portion and inclined end portions, the junctions between said horizontal and inclined end portions being reinforced by upwardly embossed portions involving horizontal portions extending inwardly from the junctions between the bolster guide columns and tension member and serving for the support of auxiliary bolster springs, and downwardly and inwardly inclined portions connecting said auxiliary spring supporting portions with the upper portion of the tension member.

7. A side frame comprising a tension member constructed as a central horizontal beam portion supported at each end by diagonal end portions with the junctions between said central and end portions reinforced by upstanding hollow bosses, the upper surfaces 40 of which assist in the support of the bolster springs and the inner sides of which slope downwardly and inwardly to join with the main portion of the tension member.

8. In a car truck, in combination, a side frame formed with compression and tension members spaced at intermediate portions thereof by bolster guide columns and leaving a window opening therebetween, the tension member beneath the window opening being 50 formed with a spring seating portion serving for the support of a nest of springs approximately square in plan, auxiliary spring supporting portions being provided adjacent the bolster guide columns above the level of the main spring portion and joined thereto by downwardly and inwardly inclined webs extending between the transversely spaced springs of the main nest of springs.

9. In a car truck, in combination, a side frame comprising a compression member, a tension member, bolster guide columns spacing intermediate portions of said members and leaving a window opening therebetween, that portion of the tension member beneath 65 the window opening involving a central

horizontal portion and inclined end portions extending therefrom beneath the bolster guide columns, embossments reinforcing the junctions between the horizontal central portion and the inclined end portions with the upper surfaces thereof serving for the support of auxiliary bolster springs, the sides thereof sloping downwardly and inwardly to join with the horizontal portion of the tension member, a spring plank supported 70 on said tension member and formed with corrugations in the sides thereof interlocking with the sloping sides of the embossments to maintain said plank in proper relation with respect to the frame, a nest of springs supported on said spring plank, auxiliary springs supported on said embossments, and a bolster with a main central portion supported on the main nest of springs and with elevated side portions resting on said auxiliary springs. 80

10. In a car truck, in combination, a side frame comprising an upper compression member, a lower tension member and columns, a spring assemblage supported on 90 said tension member between said columns, said assemblage comprising two end springs and a central group of springs, that part of the tension member on which said end springs rest being at a higher level than the intermediate part on which said central group rests and being joined to said intermediate part by inclined webs extending between transversely spaced springs of said central group. 100

11. In a car truck, in combination, side frames each comprising an upper compression, a lower tension member, and columns, a spring seat on each of said tension members between said columns, said spring seat having end sections elevated above the central section thereof, said central section being of greater width transversely of said side frame than said end sections, an assemblage of springs between said columns 105 comprising a group of intermediate springs, said intermediate springs being seated upon said central section, a single end spring at each end of said group of intermediate springs, said end springs resting upon said elevated end sections of said spring seat, some of said intermediate springs being spaced on either side of the straight line joining the centers of said end springs, and the elevated sections of the spring seat being joined to the central section thereof by webs passing between and intersecting the transverse axial planes of said spaced springs, and a bolster resting upon said assemblage of springs. 110 115 120

12. In a car truck, in combination, a side frame comprising upper and lower members and columns, a spring plank supported on said lower member between said columns, an assemblage of springs between said columns, 130

the intermediate springs of said assemblage resting on said spring plank and the outer springs resting on said lower member outside of said spring plank on upwardly em-
bossed portions thereof, said upwardly em-
bossed portions being joined to the main por-
tion of said lower member by downwardly

and inwardly inclined side portions, said spring plank being correspondingly em-
bossed to interlock with said inclined side 10
portions.

In testimony whereof I affix my signature.
